CLAIM

The ornamental design for a location tracking device as shown and described.

DESCRIPTION

FIG. 1 is a front and left side perspective view of the location tracking device showing my design.

FIG. 2 is a rear and right side perspective view of the location tracking device shown in FIG. 1.

FIG. 3 is a front elevational view of the location tracking device shown in FIG. 1.

FIG. 4 is a rear elevational view of the location tracking device shown in FIG. 1.

FIG. 5 is a left side view of the location tracking device shown in FIG. 1.

FIG. 6 is a right side view of the location tracking device shown in FIG. 1.

FIG. 7 is a top plan view of the location tracking device shown in FIG. 1; and,

FIG. 8 is a bottom plan view of the location tracking device shown in FIG. 1.

The broken lines in the drawings depict portions of the location tracking device that form no part of the claimed design.

1 Claim, 8 Drawing Sheets
